UNITED STATES PATENT OFFICE.

WILLIAM W. ALLEN, OF BALLINGER, TEXAS.

HYDRAULIC MOTOR.

SPECIFICATION forming part of Letters Patent No. 766,801, dated August 9, 1904.

Application filed November 2, 1903. Serial No. 179,626. (No model.)

To all whom it may concern:

Be it known that I, WILLIAM W. ALLEN, a citizen of the United States, residing at Ballinger, in the county of Runnels and State of Texas, have invented a new and useful Hydraulic Motor, of which the following is a specification.

This invention relates to hydraulic motors; and it has for its object to provide a device of this class which shall possess superior advantages in point of simplicity, durability, and general efficiency.

My invention has special reference to that class of hydraulic motors which are known as "current-motors" and which are usually employed in shallow and rapid streams in order to make the motive power of such streams available without the construction of dams and, in fact, without the necessity of providing elaborate and costly structures.

My present invention comprises a frame adapted to be staked or otherwise secured to the bottom or bed of a stream, said frame supporting a horizontally-disposed wheel mounted upon a vertical axis having a crank from which motion may be transmitted to the machinery to be operated.

The invention specially consists in the improved construction of the water-wheel and the buckets of the same and other structural details, as will appear when the nature of the invention is more fully understood.

The details of construction of my invention will be hereinafter more fully described, and particularly pointed out in the claims.

In the accompanying drawings, Figure 1 is a plan view of a motor constructed in accordance with the principles of my invention. Fig. 2 is a vertical sectional view. Fig. 3 is a sectional detail view taken on the line 3 3 in Fig. 1. Fig. 4 is a perspective view showing one of the buckets and related parts.

Corresponding parts in the several figures are indicated by similar numerals of reference. The base-frame of my improved hydraulic motor is composed of three metallic strips or bars 1 1 and 2, the former of which being the longer ones, which are crossed about centrally at an angle to each other. The cross-bars 1 1 are connected at what may be termed

their "rear" ends by means of a pair of arched cross-braces 3 and 4. Three arched bars 5, which are provided at their lower ends with feet 6, are connected to form a cage, which is connected with the base-frame by means of bolts 55 or other suitable fastening means connecting the feet 6 with the base members 1 and 2. The intersecting points of the base-bars and of the cage-bars are provided with bearings for a vertical shaft or axle 7, upon which is mounted the hub 8 of a water-wheel, said shaft being provided above said hub with a crank 9 for the transmission of motion.

The water-wheel is composed, besides the hub, of a plurality of spokes radiating from said hub and designated 10 and 11, the spokes 10 radiating from the upper portion and the spokes 11 from the lower end of the hub. The upper spokes 10 support a pair of concentric rings—namely, an outer ring 12 and an inner ring 13. A pair of corresponding concentric rings 12^a and 13^a are secured to the under sides of the spokes 11. The outer ends of the spokes 10 and 11 are connected by uprights 14, which support the outer ends of rods 15, the inner ends of which are suitably supported in the hub.

Each of the buckets of my improved water-wheel is composed of a pair of plates 16 and 16^a, which are hingedly connected with each other and with one of the supporting-rods 15, each of said plates being provided at its outer edge with a flange 17 17^a, the flange 17 of the upper plate 16 being turned in a downward direction, while the flange 17 of the lower plate 16^a is turned upwardly, said plates being thus overlapped, as will be readily seen. The plates 16 and 16^a are wedge-shaped or tapering, their outer ends being much wider than their inner ends, which being disposed in proximity to the hub are necessarily quite narrow, while the outer ends of the plate constituting the buckets may be of considerable width, thus forming buckets of considerable capacity. It is obvious that the lower plates will rest and be supported upon the lower rings 12^a and 13^a, which is their normal position. The normal position of the upper plates 16 will be lowered until the flanges 17 are supported upon the lower plates 16^a. When the

machine, however, is submerged below the surface of a rapidly-moving current, the tendency of the current will be to force in an upward direction the plates 16 of the buckets 5 disposed on one side of the axis of the wheel, the impact of the current serving to raise the upper plates and to rotate the wheel. The buckets upon the opposite side of the axis will, on the other hand, be closed, so as to 10 present but slight obstacle to the rotation of the wheel. The operation of the wheel naturally is continuous and requires little or no attention after the machine has once been placed in position. To place it in position, 15 all that is necessary is to slightly level the bed of the stream sufficiently to accommodate the framework and the cage containing the wheel. The machine may then be sunk and secured to the bed or bottom of the stream in 20 any suitable manner, according to the nature thereof.

In the drawings accompanying this specification I have shown a double-acting pump 20 mounted upon the cross-braces 3 and 4, the 25 piston-rod 21 of said pump being connected by a pitman 22 with the crank 9 of the shaft 7. In the example illustrated the pump is provided with duplicate escape-spouts 23, which converge into a single discharge-spout 24, 30 which may be connected by hose or in any suitable manner with the place of delivery. The shaft 7 may also be provided at its upper end with a gear-wheel 25 or other suitable means from which motion may be transmitted 35 to any machinery that it may be desired to drive by the power derived from the motor.

I have in the foregoing described a simple and preferred construction of my improved hydraulic motor; but I desire it to be understood 40 that I do not necessarily limit myself to the precise structural details herein set forth, but reserve the right to any changes,

alterations, and modifications which may be resorted to within the scope of my invention and without departing from the spirit or sacrificing the utility of the same. 45

Having thus described my invention, I claim—

1. In a device of the class described, a base-frame composed of members radiating from a common center, a cage composed of arched bars intersecting each other at a point in perpendicular alignment with the center of the base-frame, said arched bars having feet securely connected with the members of the base-frame, a crank-axle journaled at the points of intersection of the members of the base-frame and of the members of the cage, and a current-wheel mounted upon said axle, 55 said wheel comprising a hub, spokes radiating from the upper and lower ends of said hub, concentric rings connected with said spokes, vertical braces connecting the outer ends of the upper and lower spokes, rods connecting said braces with the hub, and foldable buckets comprising flanged plates hingedly connected with each other and with the 60 said rods. 65

2. In a device of the class described, a current-wheel comprising a hub, spokes radiating from the upper and lower ends of said hub, vertical braces connecting the outer ends of said spokes, rods connecting said braces with the hub, and tapering plates connected hingedly, in pairs, with said rods and overlapping flanges at the outer ends of said plates. 70 75

In testimony that I claim the foregoing as my own I have hereto affixed my signature in the presence of two witnesses.

WILLIAM W. ALLEN.
